(57) **CLAIM**

The ornamental design for a wax warmer, as shown and described.

DESCRIPTION

FIG. 1 is a top perspective view of a wax warmer showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 2; and,

FIG. 10 is an enlarged view of portion 10 of FIG. 8.

The broken lines in the figures depict portions of the wax warmer that form no part of the claimed design.
